CLAIM

I claim the ornamental shape of an IV tube carriage device,
as shown and described.

DESCRIPTION

FIG. 1 is a top perspective view of an IV tube carriage device;

FIG. 2 is a front view;

FIG. 3 is a right-side view;

FIG. 4 is a rear view;

FIG. 5 is a left-side view;

FIG. 6 is a top view; and,

FIG. 7 is a bottom view.

The broken lines in the drawings illustrate portions of the IV
tube carriage device and form no part of the claimed design.

1 Claim, 3 Drawing Sheets
